SEAT GRINDER

Laurence F. Shesler, Yonkers, N. Y.

Application March 23, 1956, Serial No. 573,532

4 Claims. (Cl. 51—241)

This invention relates to a refinisher for valve seats and more particularly, to a refinisher for the valve seat in a faucet.

Faucets tend to leak with the passage of time because of the considerable and continued water pressures which wear upon the valving arrangement provided therefor, more particularly, the relatively thin walled valve seat. Although a leaky faucet can be repaired simply by grinding the irregular and worn valve seat to its original smooth state, special equipment and knowledge is required for the operation because if the seat is not ground properly the faucet will continue to leak, possibly even more than before the unsuccessful repair job. One of the chief reasons for improper grinding, even with trained personnel, is that it is difficult to properly align conventional grinding devices with the valve seat. Moreover, conventional grinders are heavy tools, hard to operate, expensive to manufacture, and difficult to carry from place to place.

Accordingly, it is one of the primary objects of the present invention to provide a valve seat refinisher which can be successfully utilized by persons having no previous training.

It is another important object of the present invention to provide a valve seat refinisher which necessarily must properly align itself with the valve seat.

It is a further object of the present invention to provide a valve seat refinisher which is simple in structure and inexpensive to make.

It is another object of the present invention to provide a valve seat refinisher which is made of sturdy but light weight materials and which may be readily carried from place to place.

It is still a further object of the present invention to provide a grinding device wherein the washer for the valve to be ground is utilized to insure perfect grinding.

Briefly stated, the valve seat refinisher of the present invention comprises a yieldable centering member adapted to be securely fitted into the interiorly threaded portion of a tubular mounting for a faucet closure member, a rod-like support member, the said centering member being slidably and rotatably mounted on said rod-like member, a washer for the faucet valve seat affixed to the said rod at one end thereof, and an abrasive member superposed upon the said washer for engagement with the valve seat.

A fuller understanding of the invention and the manner in which its objectives and advantages may be realized will become apparent from the following detailed description thereof taken in connection with the accompanying drawings wherein:

Fig. 1 is a side elevation of an embodiment of the seat grinder of the present invention shown assembled in working relationship with the lower portion of a faucet whose wall has been partly broken away;

Fig. 2 is a sectional view of a portion of another embodiment of the seat grinder of the present invention shown fitted into the interiorly threaded section of the lower portion of a faucet as in Fig. 1;

2

Fig. 3 is a side elevation of yet another embodiment of the seat grinder of the present invention shown assembled in working relationship with the lower portion of a faucet whose wall has been partly broken away; and

Fig. 4 is a plan view of the abrasive disc utilized in the seat grinder of the present invention.

Referring now to the drawing and more particularly to Fig. 1 thereof wherein one of the embodiments of the present invention is shown, the seat grinder designated generally by the numeral 10 is shown extending into the tubular body of a faucet 12, the closure member for the said faucet having been removed therefrom.

The seat grinder consists, in this particular embodiment of the invention, of a rod 14 upon which a centering member 16 made of cork is supported, the said rod passing through an axial bore formed in the centering member 16. The respective diameters of the bore and the rod are such that the centering member is slidably and rotatably mounted on the said rod.

20 A handle 18 is rigidly affixed to one end of the rod so that the rod may be gripped as hereinafter explained. The rod is threaded at the other end thereof so that pliable abrasive disc 20 backed by conventional faucet washer 22 may be affixed thereto by means of nut 24. As will be hereinafter explained, after the valve seat has been ground smooth, tapered washer 22 will be removed from the grinder and will be actually utilized in association with the valve seat of the assembled faucet.

Centering member 16 may be interchanged with centering members of varying diameters, the size of the centering member for a particular grinding job being governed by the diameter of the interiorly threaded section of the faucet. Likewise, the abrasive discs and washers utilized are selected in accordance with the size of the 35 valve seat being refinished. In other words, the device of the present invention may be readily utilized for refinishing the valve seats of faucets of any size simply by a mere interchange of the above noted elements. It may be added in this connection that the size of the 40 components comprising a faucet are more or less standardized.

In practice, after the valve closure member has been removed from the faucet, the grinding device is inserted therein, as shown in the drawing. Cork 16 is then slid 45 down the rod until it contacts the interiorly threaded portion 26 of the faucet where originally the valve closure member had been mounted, and is then screwed into the interiorly threaded portion 26, the threads biting into the cork as it is screwed in place so that it is rigidly and firmly held in place when fully inserted into portion 26.

Once the cork is inserted as aforesaid, the rod 14 is depressed until abrasive 20 contacts valve seat 28. By rotating rod 14 with abrasive 20 in contact with the valve seat, the valve seat is accurately and readily ground 55 smooth.

I have found that unusually accurate grinding may be obtained without any difficulty by providing a centering member having a yieldable or compressible composition. In the embodiment of my invention shown in 60 Fig. 1, a centering member composed of cork was primarily instrumental in making an unusually delicate and very difficult grinding operation one that an unskilled individual or even a child could carry out. However, it is not intended to restrict the invention to the utilization 65 of cork or cork-like centering members because I have found that similar results may be obtained if the centering member is of a yieldable and/or compressible nature. Unusually good results, however, have been obtained with centering members of cork or cork-like composition because when such centering members are inserted within portion 26 of the faucet, the threads located 70 thereat bite into the centering member causing

same to follow the threads and thereby facilitating a perfect alignment of the tool with the seat to insure accurate grinding.

In Figs. 2 and 3, embodiments of the grinder are shown wherein the centering member is of a rubber or rubber-like composition. In these particular embodiments of the grinding device, rod 14 extends through a threaded sleeve 30, the rubber centering member being mounted upon the said sleeve. In practice, the centering member shown in Fig. 2 is inserted into portion 26 of the faucet and by turning winged nut 32 against metal washer 34, the centering member is compressed between members 34 and 36 and thereby expanded to fill the grooves between the threads of threaded portion 26 thereby being rigidly and firmly held in place in portion 26 and further, following its threads to insure perfect alignment of abrasive and valve seat.

In Fig. 3, the interiorly threaded bonnet of the faucet is itself utilized to compress the rubber centering member as aforesaid. After the removal of the faucet closure member, the grinding tool is assembled with bonnet 38 as shown in the drawing. The centering member is first inserted into portion 26 of the faucet and the bonnet slipped over portion 26 and screwed tightly thereupon causing the compression and expansion of the centering member as aforesaid. Rod 14, in this particular embodiment in the form of a crank, is then depressed so that abrasive 20 contacts valve seat 28 and the device is ready for use.

Of course, the invention does not solely reside in the use of a yieldable and/or compressible centering member but in the utilization of the described combination as a whole, particular attention being paid to the tapered washer 22 and the positioning thereof, amongst other things.

It thus may be seen that by this invention, a seat grinder has been provided where alignment is of no problem because the grinder is more or less self-aligning permitting untrained and unprofessional persons to successfully operate same. Moreover, by not requiring a massive and unyieldable centering member, the weight of the grinder is markedly reduced thereby facilitating the carrying of the grinder from place to place. Furthermore, the grinder, as has been seen, is made of readily available and inexpensive parts and can be readily made up by hand.

Although the invention has been described in detail with respect to several preferred embodiments thereof, it will be understood by those skilled in the art, after reading this specification, that various changes and modifications may be made without departing from the spirit of the invention and the scope of the appended claims.

What is claimed as new and desired to be secured by Letters Patent is:

1. A valve seat refinisher for a valve having an interiorly threaded housing comprising a centering member of yieldable composition, said centering member being adapted to be compressed by the threads of the interiorly threaded housing so as to mesh with the same when the centering member is expanded in the housing, means associated with said centering member for expanding the same in the housing, a rotatable shaft, the centering member being slidably and rotatably mounted on said shaft, the valve seat end of said shaft being adapted to support abrasive means for refinishing the valve seat.
- 15 2. A valve seat refinisher for a valve having an interiorly threaded housing comprising a centering member of yieldable composition, said centering member being adapted to be compressed by the threads of the interiorly threaded housing so as to mesh with the same when the centering member is expanded in the housing, means associated with said centering member for expanding the same in the housing, a rotatable shaft, a sleeve slidably and rotatably mounted on said shaft, said yieldable centering member and the means for expanding the centering member in the housing being mounted on said sleeve, the valve seat end of said shaft being adapted to support abrasive means for refinishing the valve seat.
- 20 3. A valve seat refinisher for a valve having an interiorly threaded housing comprising a centering member of yieldable composition, said centering member being adapted to be compressed by the threads of the interiorly threaded housing so as to mesh with the same when the centering member is expanded in the housing, means associated with said centering member for expanding the centering member in the housing being mounted on said sleeve, the valve seat end of said shaft being adapted to support abrasive means for refinishing the valve seat.
- 25 4. The refinisher according to claim 3 wherein the sleeve is externally threaded and the means for expanding the centering member comprises a wing nut threaded on said sleeve.
